CLAIM

The ornamental design for a set of smart locks, as shown and described.

DESCRIPTION

FIG. 1 is a front, right and top perspective view of a set of smart locks, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1.

The broken lines show portions of the set of smart locks that form no part of the claimed design. The dash-dash broken lines represent boundaries of the claimed design and form no part of the claimed design.

The dot-dash broken lines surrounding the detail views shown in FIGS. 1 and 9 are for annotative purposes only and form no part thereof.
